CIGARETTE LIGHTER

Edith J. Pitts, Attleboro, Mass., assignor to Lambert Engraving Company, Inc., a corporation of Massachusetts

Filed Aug. 23, 1963, Ser. No. 76,334

Term of patent 3½ years

(Cl. D48—27)

F I G. 1

F I G. 2

FIG. 1 is a side elevational view of the cigarette lighter showing my new design;

FIG. 2 is a bottom view thereof.

The dominant portion of my design resides in the portions shown in full lines. The undisclosed side of the lighter is substantially the same in appearance as the side shown except that the body portion is flat and unornamented.

I claim:

The ornamental design for a cigarette lighter, substantially as shown and described.
